UNITED STATES PATENT OFFICE

2,468,356

ON-OR-OFF ELECTRIC SWITCH

Paul R. Bortfeld, Milwaukee, Wis.

Application April 14, 1947, Serial No. 741,244

3 Claims. (Cl. 200—35)

1

This invention relates to switches, and more particularly, has reference to a device whereby an electric switch may be automatically closed at a predetermined time, or opened, as desired.

The primary object of the invention is to provide a device that is readily capable of attachment to a conventionally constructed clock and electric switch, whereby they may be adapted for automatically supplying or cutting off power to various types of electric fixtures, such as lamps, radios, and the like.

Another important object of the invention is to provide a device of the character described which can be constructed with a minimum of materials, but which is, nevertheless, adapted to perform its functions in an unusually efficient manner.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawing

Figure 1 is an end elevational view of an automatic switch actuating device constructed in accordance with the invention.

Figure 2 is a top plan view.

Figure 3 is a rear elevational view.

Figure 4 is a perspective view showing my device, whereby power taken from the rotatable alarm shaft of a clock is adapted to actuate an electric switch, a portion of the device being broken away.

Figure 5 is a perspective view of a modification.

Referring to the drawing in detail, 5 designates an alarm clock of conventional construction, that is fixedly mounted on a flat platform 6, by screws 7 or other suitable fastening means.

Mounted rearwardly of the clock 5, by means of screws 8 or other suitable fastening means is a switch 9, which preferably is of the lever type. This is disposed substantially centrally relative to the clock, so that the laterally extended end of its switch arm is positioned approximately below the alarm shaft of the clock. Wires 10, one of which leads to a source of electric power (not shown), and the other of which leads to an electric fixture, such as a lamp (not shown), extend from the switch, in the conventional manner.

The switch is also equipped with a pull chain 11 which may be of the bead type.

2

Extending from the rear of the alarm clock 5 is the threaded alarm shaft 12.

The above-described objects are of conventional construction, and do not in themselves constitute part of the present invention.

In place of the customary operating handle normally threaded on the alarm shaft 12, there is threaded thereon the adapting device constructed in accordance with the present invention. This is formed with a substantially cylindrical body portion 13, which is provided with a bore extending inwardly from one end that is threaded for engagement with the alarm shaft 12. From the side walls of the body portion 13 opposed handles 14 are extended outwardly, for the purpose of permitting mounting of the body portion upon the alarm shaft with more facility.

The other end of the body portion 13 is closed, and rigidly connected thereto is one end of a relatively thin straight-formed spindle 15. This is extended outwardly relative to the body portion 13, in a line parallel but spaced from the axis of the body portion.

Substantially diametrically disposed from the spindle 15 is a second spindle or stem 16, which, as compared to the spindle 15, is of thickened formation. This is also rigidly connected to the closed end of the body portion 13 and is extended outwardly therefrom in a line parallel to the axis of the body portion.

The free end of the stem 16 is formed with a flanged collar 17, a part of the periphery of which is cut away to provide a substantially semi-circular notch 18. The collar 17 is so proportioned and disposed relative to the spindle 15 as to embrace the spindle 15, the dimensions of the notch, however, being such as to provide an arcuate space between the wall of the spindle 15 and the wall of the notch 18. Preferably, the free end of the spindle 15 projects beyond the free end of the stem 16. Longitudinally, the stem 16 is formed with a curvingly depressed inner wall 18', the stem 16 being also formed with a curved outer wall, as clearly shown in Figure 4, which serves as a bearing surface.

The spindle 15 is adapted to receive one end of a strap 19, having the loop 20 whereby the strap may be detachably connected to the spindle. The other end of the strap 19 is provided with a key hole slot 21, in which can be firmly engaged the end of the pull chain 11. It is understood that the formation of the key hole slot permits its engagement of the pull chain 11 at any desired point longitudinally of the pull chain.

55 The strap 19, in the embodiment illustrated,

is formed of a length of rigid metallic material. However, it is believed to be sufficiently obvious as not to require illustration that it may alternatively be formed from a length of flexible material, such as cloth or leather, in which event the slot 21 could be cut through a metal tab or the like clamped on to the end of the flexible strap.

In operation of my device, the loop 20 is slipped over the free end of the spindle 15, and positioned intermediate the collar 17 and the closed end of the body portion 13. The pull chain 11 is then inserted in the key hole slot 21 at the desired point, the chain being preferably connected thereto at a point at which the chain will be substantially taut. The alarm on the clock 5 is then set for actuation at a predetermined time, and the alarm button 22 pulled out to permit actuation of the alarm. At the specified time, the alarm shaft 12 rotates, rotating the body portion 13, and causing the spindle 15 and stem 16, which as stated are diametrically opposed relative to the body portion 13, each to travel in an arcuate path around the axis of the alarm shaft 12. This results in the strap 19 being engaged by one side edge of the depressingly curved inner wall 18' of the stem 16. If the strap 19 is of the rigid type, the outer end thereof, to which the pull chain 11 is attached, travels in a wide arcuate path around the axis of the alarm shaft 12. The switch arm to which the pull chain 11 is attached is accordingly moved to the dotted line position shown in Figure 3, actuating the switch 9 to close or open the circuit as desired.

Should the strap 19 be of the flexible type, the outer wall of the stem 16 serves as a bearing surface, together with the diametrically opposed outer wall of the spindle 15, causing the strap to be wound thereupon, actuating the switch 9 after it has been wound to a specific extent.

In Figure 5, there has been shown a modification of the adapting device in which the body portion has been designated by the numeral 23. This is formed substantially identically to the body portion 13 hereinbefore described. However, projecting from the closed end thereof is a plurality of parallel spaced apart spindles, all of relatively small diameter. These are all disposed away from the axis of the body portion 23, so that each travels in an arcuate path around said axis. In use of this modification, the loop 20 is positioned over any of the spindles 24, so that the strap will be engaged and swung by one of the other spindles in the same manner as it is engaged and swung by member 16 of the form of Fig. 4.

Referring again to the first embodiment of the invention, it is pointed out that the particular arrangement and formation of the spindle 15 and stem 16 is such that while the strap 19 may

be easily positioned thereon, it cannot be accidentally removed after the device has been set for operation.

What is claimed is:

1. The combination, with a clock having an alarm shaft and with an electric switch having a pull chain, of a body portion mounted on the shaft to rotate therewith, a plurality of spindles extended from the body portion and offset from and disposed parallel to the shaft axis, an elongated rigid strap, a loop on one end of the strap detachably passed over one of the spindles, and a detachable and adjustable connection between the other end of the strap and the chain, said strap being engageable adjacent the loop by another of the spindles on rotation of the alarm shaft, for swinging of the last-named end of the strap in a wide arc.
2. The combination, with a clock having an alarm shaft and with an electric switch having a pull chain, of a body portion mounted on the shaft to rotate therewith, a pair of spindles extended from the body portion and offset from and disposed parallel to the shaft axis, a flanged collar on the free end of one of the spindles having a peripheral indentation through which the other spindle extends, said other spindle being spaced from the wall of the indentation, an elongated rigid strap, a loop on one end of the strap detachably passed over said other spindle, and a detachable and adjustable connection between the other end of the strap and the chain, said strap engageable adjacent the loop by the first-named spindle on rotation of the alarm shaft for swinging of the last-named end of the strap in a wide arc.
3. The combination, with a clock having an alarm shaft and with an electric switch having a pull chain, of a body portion mounted on the shaft to rotate therewith, a plurality of spindles, amounting in number to at least three, extended from the body portion and offset from and disposed parallel to the shaft axis, an elongated rigid strap, a loop on one end of the strap detachably passed over any one of the spindles, and a detachable and adjustable connection between the other end of the strap and the chain, said strap engageable adjacent the loop by a selected other spindle on rotation of the alarm shaft for swinging of the last-named end of the strap in a wide arc.
